UNITED STATES PATENT OFFICE.

FRANK C. LA MAR, OF PITTSBURGH, PENNSYLVANIA.

RENEWABLE ELECTRIC FUSE.

Application filed April 30, 1921. Serial No. 465,819.

To all whom it may concern:

Be it known that I, FRANK C. LA MAR, a citizen of the United States, residing at Pittsburgh, in the county of Allegheny and 5 State of Pennsylvania, have invented a new and useful Improvement in Renewable Electric Fuses, of which the following is a specification.

This invention relates to renewable or refillable electric fuses of the cartridge or enclosed type.

The object of the invention is to provide a renewable or refillable fuse preferably of the knife-blade type, of simple, economical and efficient construction, and which may readily be assembled and as readily disassembled when blown, for the removal of the blown or ruptured fuse element or strip, and refilling or reloading the fuse with a 20 new fuse element.

Another and important object of the invention, is to provide a cartridge fuse of this type, in which the metallic parts of the fuse and particularly those parts constituting the 25 locking means for securing the end caps or other removable devices for closing the ends of the shell or casing, are protected from the molten metal of the burned fuse which is carried toward the ends of the casing by the 30 gases created within the casing by the explosion of the fuse, in seeking their escape at the ends of the casing, thereby preventing such molten metal from finding its way between the parts and effectively soldering or 35 forming a union between such parts and locking them together in such a way that the removal by hand manipulation of the end caps or closures is rendered difficult and impossible, and making it necessary to employ 40 a vise and a wrench or other tools to remove the end closures for disassembling the fuse for reloading.

The invention consists, in a refillable or renewable fuse, comprising a casing or shell 45 of insulating material, metallic ferrules permanently fixed upon the ends of the casing, knife-blade terminals, and disks carried thereby, a fuse strip fixed to and carried by said knife-blade terminals and disks, and 50 screw threads on one or more of said disks and ferrules, said knife-blade terminals and their attached disks and said fuse element adapted to be assembled in a unitary structure and fitted in said casing and screwed 55 to place.

The invention further consists in a refillable fuse comprising a shell or casing of insulating material having means for positioning a fuse element therein, end closures for the shell or casing, and disks of fibre or other refractory and non-metallic material fitted upon and carried by said fuse positioning means, and covering said end closures upon the interior of the shell, all substantially as I will proceed now more particularly to set forth and finally claim.

In the accompanying drawings illustrating the invention, in the several views of which like parts are similarly designated, Figure 1 is a side elevation of the fuse. Fig. 70 2 is a vertical longitudinal section. Fig. 3 is a plan or elevation of the knife-blade terminals, end caps or closures and fuse strip in assembled condition. Fig. 4 is a longitudinal section of a modified form of fuse, 75 and Fig. 5 is a longitudinal section of another modified form of fuse.

In the drawings, 1 is the shell or casing of fibre or other suitable insulating and refractory material. 2 and 3 are metallic ferrules, preferably of brass, permanently fixed 80 upon the ends of the shell or casing by means of pins 4.

As shown in Fig. 2, the ferrule 2 is provided with an inwardly projecting thickened 85 portion 5 to reduce the opening at the outer end of the ferrule to a diameter slightly less than the interior diameter of the opening in the shell or casing, and affording a shoulder or stop 6 within the ferrule to abut 90 against the end of the shell or casing when assembling the parts. The thickened portion 5 of the ferrule is provided with an interior screw thread 7 for a purpose presently appearing.

The ferrule 3 on the opposite end of the shell or casing is also provided with an inwardly extended thickened portion at its outer end, as at 8, to provide a bore therein of a diameter coinciding with the interior 100 diameter of the shell or casing, and said thickened portion is reduced at its outer edge and provided with a screw thread 9, to receive a screw-threaded clamping ring 10, having an inwardly extending annular flange 11 surrounding an annular opening 11' in the end of the clamping ring to permit the turning of the clamping ring about the knife-blade in screwing the ring to place.

The shell or casing as thus constructed 11.

is adapted to receive the fuse carrying and supporting elements as illustrated in Fig. 2, and shown in detail and in assembled condition or as a unitary assemblage in Fig. 3, 5 ready for assembling in the shell or casing.

As shown in Figs. 2 and 3 the fuse carrier or supporting device comprises the end terminals or contacts 12 and 13, herein shown as of the ordinary knife-blade type, having 10 the flat reduced shanks or terminals 14 and 15 respectively, to which the fuse strip 16 is removably connected at its ends in any usual or suitable manner, as by bolts 17 and nuts 18.

15 Mounted upon the shank 14 of the terminal blade 12 or constructed integrally therewith and adjacent to and engaging the terminal blade 12, is an annular disk or plug 20 of metal 19 having its outer or forward end screw-threaded, as at 20, and at its inner end and adjacent to the screw-threads 20 provided with an annular circumferential groove or depression 21 for a purpose presently appearing. The screw-threaded disk 25 or plug 19 is of a slightly less diameter than the bore of the ferrule 3 to permit it to be inserted in the end of the shell carrying the ferrule 3 and slid through the casing and screwed into the interior screw-threads 7 of the ferrule 2 at the opposite end of the shell or casing to form a closure for that 30 end of the shell or casing.

Mounted upon the shank 15 of the terminal blade 13 and abutting against the blade 13, or constructed integrally with these parts, is a disk or plug of metal 22 having a smooth or unthreaded periphery, and of a diameter to fit loosely but closely and snugly in the bore of the ferrule 3, to form a 35 closure for this end of the shell or casing, and engaging a shoulder 9' formed on the interior of the ferrule 3.

40 In assembling the fuse as thus constructed, the ring 10 having been removed from the end of the shell or casing, the fuse strip and its carrying and supporting terminals or parts having been assembled in a unitary structure as shown in Fig. 3, the leading end thereof carrying the screw-threaded 45 plug or disk 19 is placed in the end of the casing carrying the ferrule 3 and passed through the shell until the terminal blade 12 emerges from the opposite end of the casing and the casing grasped by one hand and with the other hand the terminal blade 12 may be grasped and turned in a counter-clockwise direction or the shell or casing turned in a clockwise direction and the terminal blade held stationary and the plug or 50 disk 19 screwed to place within the ferrule 2 thus forming a closure or seal for this end of the casing, and the disk or plug 22 drawn into the ferrule 3 at the opposite end of the shell or casing to form a closure 55 or seal for that end of the shell.

or casing, and then the ring 10 placed over the terminal blade 13 and screwed upon the threaded end of the ferrule 3 with its flange 11 engaging the end of the ferrule and the disk 22 and effectually sealing 70 the joint between said disk and ferrule against a too free escape of gases and products of combustion at this end of the fuse, and securely locking the parts in place.

As shown in Fig. 4 the shell or casing is 75 provided with interiorly screw-threaded ferrules 2', 2', at both ends, and exteriorly screw-threaded plugs or disks 19^a, 19^b, substantially similar to the plug at the left of Fig. 2 are fixed upon the knife-blade terminals or fuse-strip carrier or support, and in this arrangement, the threaded portions of the ferrule and the plug or disk at the right are of slightly larger diameter than the corresponding parts at the left, so that the plug 80 at the left may freely pass through the ferrule at the right, in assembling the fuse, and forced through the shell or casing, and by grasping the shell in one hand and turning the knife-blade terminal at the right, the 85 fuse carrier may be screwed to place in the end ferrules, the disks or plugs serving as closures or seals for the ends of the casing. In this form of the device the fuse strip 90 16 is bridged by a bar or strip 23 of fibre or other suitable insulating and refractory material secured to the opposite sides of the shanks 14 and 15 of the terminals by the bolts 17 which fasten the fuse strip to said shanks, and thus affording a rigid connection 100 between the fuse strip carrying terminals to prevent twisting of the fuse-strip when turning or screwing the fuse and its carrier to place.

In Fig. 5 the construction is substantially 105 similar to that shown in Figs. 2 and 3, excepting that the projecting threaded portion of ferrule 2 on the left-hand side is considerably less than in Figs. 2 and 3 so that in assembling the fuse, the threads of plug 19 110 will project beyond the ferrule to receive a clamping ring 10' similar to the clamping ring at the opposite end of the fuse, as in Fig. 2, and in said Fig. 5. This form of the 115 fuse is assembled in the same manner as the assemblage of the fuse of Fig. 2, excepting the final step of applying the clamping ring at the left hand end.

In order to prevent the accumulation of 120 molten metal due to the blowing or burning of the fuse strip upon the occurrence of short circuit or overload, at the ends of the fuse in and about the screw-threaded connections between the ferrules and the closures or plugs, and which it has been found 125 in effect solders or forms a tight union between the parts of fuses of this sort and renders them difficult to disassemble without the use of tools, I provide washers or disks 24, of fibre or other suitable insulating 130

- and refractory material, fixed or mounted upon the shanks 14 and 15 of the end terminals and lying closely against the closure disks or plugs and of such diameter as to fit closely and tightly the interior diameter of the end ferrules but permitting the escape of the gases at the ends of the fuse and effectively checking the passing of the molten particles of metal of the burned fuse 10 therebeyond and into and between the screw-threaded or other adjacent parts of the end closures and thereby avoiding the sticking or soldering of the parts against ready disassembly by hand. It has been found that 15 the metallic particles of the burned fuse will not stick or adhere to the fibre washers when a fuse is blown, but merely fall back into the casing, in a loose condition, and are readily emptied from the casing 20 when the fuse is disassembled for reloading.

The assembling of the fuse and the disassembling thereof for reloading will readily be understood from the drawings and the above description, and further description 25 thereof is deemed unnecessary.

When a fuse of the description herein, is blown or ruptured by a short circuit or overload in the circuit in which the fuse is connected, the gases created by the explosion 30 or burning of the fuse strip will escape past the washers 24 and the disks 22 and at the ends of the fuse provided with the screw-threaded connections, the gases after passing the washers 24 will enter the 35 annular grooves 21 in the screw-threaded plugs or disks, which grooves afford an expansion chamber or channel for the gases, and from which the gases will find their escape through the screw-threaded connection 40 between the plugs and ferrules, to the atmosphere.

In the construction shown in Figs. 2 and 5 of the drawings, the disks 22 fixed to the terminals 13 have a loose fit or are capable 45 of a slight rotary movement in the end ferrules, while the plugs or closures at the opposite ends are in rigid engagement with the ferrules, and by this arrangement it will be observed that should the spring contacts on the switch block or support to which the fuses are applied be out of alignment, and which is quite frequently found to be the case, the knife-blade terminal 13 carrying the smooth or plain disk 22, in applying the fuse to the switch block or support, will automatically align itself with or compensate for the non-aligning spring clips or contacts on the switch block, and thereby avoid skewing of the knife-blade with 55 relation to the spring contacts and producing sparking gaps between the blade and contacts, and effecting good and positive contact between the entire width of the blade and contacts and avoiding sparking there- 60 between.

What I claim is:—

1. A renewable cartridge fuse, comprising a tubular casing of insulating material, metallic ferrules permanently fixed on the ends of said casing, and a fuse-strip carrier adapted to be slipped endwise into said casing and secured in said casing by screw-threaded engagement between the ferrules and said fuse-strip carrier upon relative rotation between the casing and its attached 70 ferrules and the fuse-strip carrier.

2. A renewable cartridge fuse, comprising a tubular casing of insulating material, metallic ferrules permanently fixed on the ends of the casing, and a fuse-strip carrier comprising end terminals to which said fuse-strip is connected and plugs mounted upon said terminals, said fuse carrier adapted to be slipped endwise into said casing and secured therein by screw-threaded engagement 80 between the ferrules and said plugs upon relative rotation between the casing and said fuse-strip carrier, said plugs serving as closures for the ends of the casing.

3. A renewable cartridge fuse, comprising a tubular casing of insulating material, metallic ferrules permanently fixed on the ends of the casing, and a fuse-strip carrier comprising end terminals to which said fuse-strip is connected and plugs mounted upon 90 said terminals, said fuse carrier adapted to be slipped endwise into said casing and secured therein by screw-threaded engagement between the ferrules and said plugs upon relative rotation between the casing and said fuse-strip carrier, said plugs serving as closures for the ends of the casing, and non-metallic washers mounted upon said terminals adjacent to the inner sides of said plugs and fitting closely in said ferrules. 100

4. A renewable electric fuse, comprising a tubular casing of insulating material, an interiorly screw-threaded ferrule permanently fixed to one end of said casing, an exteriorly screw-threaded ferrule permanently fixed to the other end of said casing and having an internal diameter slightly greater than the interiorly screw-threaded ferrule at the opposite end of the casing, a fuse-strip carrier comprising end terminals, an exteriorly screw-threaded plug mounted on one of said terminals, a plain disk mounted on the other terminal, and a fuse-strip connected at its ends to said terminals, the said fuse-strip carrier adapted to be slipped endwise into said casing with its externally screw-threaded plug in engagement with the internally screw-threaded ferrule on the end of the casing and adapted to be screwed thereinto by relative rotation between the 110 casing and fuse-strip carrier and drawing the plain disk in the opposite end of the casing thereby closing both ends of the casing, and a clamping ring adapted to be screwed upon the exteriorly threaded fer- 120 125 130

rule on the end of the casing and engaging said plain disk.

5. A renewable electric fuse, comprising a tubular casing of insulating material having a fixed interior screw-thread, and a fuse-strip carrier, comprising end terminals to which the fuse-strip is connected at its ends, and plugs fixed to said terminals, the said fuse-strip carrier adapted to be inserted endwise into said casing and secured therein by screw-threaded engagement with the casing upon relative rotation between said casing and fuse-strip carrier, and said plugs serving as closures for the ends of the casing.
10. 6. A renewable electric fuse, comprising a tubular casing of insulating material, an internally threaded ferrule fixed to the end of the casing, and a fuse-strip carrier, comprising end terminals to which the fuse-strip is connected at its ends, and an exteriorly screw-threaded plug fixed to one of said terminals, the said fuse-strip carrier adapted to be slipped endwise into said casing and secured therein by screw-threaded engagement between said ferrule and plug, said plug affording a closure for the end of the casing, and said plug having an annular groove at its inner end adjacent to the screw-threads thereon, to afford an expansion chamber for gases escaping through the screw-threaded connection at the end of said casing.

7. A renewable electric fuse, comprising a tubular casing having a fixed interior screwthread at one end, and a fuse-strip carrier comprising knife-blade terminals to which a flexible fuse-strip is connected at its ends, disks carried by said terminals, one of

said disks having a screw-threaded portion adapted to engage the interiorly screw-threaded end of said casing by relative rotation between said casing and fuse strip carrier, and the other of said disks fitting loosely in the opposite end of said casing whereby the knife-blade terminal fixed thereto will automatically align itself with the spring contacts of a switch block or base.

8. In a renewable electric fuse, a casing of insulating material, a fuse element mounted in said casing, a screw-threaded ferrule fixed to the end of said casing and provided with an interior integral inwardly projecting shoulder intermediate the ends of the ferrule, a disk for supporting said fuse element in the casing fitted in said ferrule and adapted to seat against said shoulder, and a screw-threaded cap fitted to said ferrule and engaging said disk to hold it in engagement with said shoulder.

9. In a renewable electric fuse, a casing of insulating material, a fuse element mounted in said casing, an exteriorly screw-threaded ferrule fixed to the end of the casing and provided with an integral interior inwardly projecting shoulder intermediate the ends of the ferrule, a disk for supporting said fuse element in the casing fitted in said ferrule and adapted to seat against said shoulder and projecting slightly beyond the end of the ferrule, and an interiorly screw-threaded cap fitted upon said ferrule and adapted to engage said disk to hold it in engagement with said shoulder.

I have hereunto set my hand this 22 day of April 1921 at Pittsburgh, Pa.

FRANK C. LA MAR.
